GARDEN CENTER BUILDING

Frank T. McCoy, Jr., Nashville, Tenn., assignor to Hardi-Gardens, Inc., Nashville, Tenn.

Filed Dec. 9, 1969, Ser. No. 20,417

Term of patent 14 years

Int. Cl. D25—04

U.S. Cl. D13—1

FIG. 1

FIG. 2

FIG. 3

FIG. 4

FIG. 5

FIG. 6

FIG. 7

FIG. 8

FIG. 9

FIG. 10

FIG. 1 is a front elevational view of a garden center building showing my new design;

FIG. 2 is a rear elevational view thereof;

FIG. 3 is a side elevational view thereof as seen from the left of FIG. 1;

FIG. 4 is a side elevational view of the building as seen from the right of FIG. 1;

FIG. 5 is a front elevational view of a modified form of the building of FIG. 1 with the shed omitted;

FIG. 6 is a front elevational view of another modified form of the building of FIG. 1;

FIG. 7 is a rear elevational view of FIG. 6;

FIG. 8 is a side elevational view of the building as seen from the left of FIG. 6;

FIG. 9 is a side elevational view thereof as seen from the right of FIG. 6; and

FIG. 10 is a front elevational view of a modified form of the building of FIG. 6 with the shed omitted.

I claim:

The ornamental design for a garden center building, substantially as shown and described.
